[57] CLAIM

The ornamental design for a heavy duty, remotely controlled timer switch, as shown and described.

DESCRIPTION

FIG. 1 is a front elevational view of a heavy duty, remotely controlled timer switch showing my new design.

FIG. 2 is a right hand side elevational view thereof.

FIG. 3 is a top plan view thereof.

FIG. 4 is a bottom plan view thereof.

FIG. 5 is a left hand side elevational view thereof.

FIG. 6 is a back elevational view thereof.

FIG. 7 is a perspective view thereof.
